UNITED STATES PATENT OFFICE.

NILS O. LINDSTROM, OF NUTLEY, AND CARL F. E. OLOFSON, OF WEST ORANGE, NEW JERSEY, ASSIGNORS TO ALONZO B. SEE, OF BROOKLYN, NEW YORK.

ELEVATOR.

Application filed January 10, 1923. Serial No. 611,732.

To all whom it may concern:

Be it known that we, NILS O. LINDSTROM and CARL F. E. OLOFSON, citizens of the United States, residing at Nutley, county 5 of Essex, State of New Jersey, and West Orange, county of Essex, and State of New Jersey, respectively, have invented certain new and useful Improvements in Elevators, of which the following is a full, clear, and 10 exact description.

This invention relates to elevators and particularly to power-actuated door operating devices for the car and shaftway doors. In elevators and other conveyances, where 15 doors must be frequently operated, and where their manual operation is inconvenient, prior devices for the power operation of the doors have been unsatisfactory for various reasons, such as because of the impossibility of operating the doors rapidly by simple and reliable mechanism, and checking the final closing movement without impact or slamming, and also because of danger or injury to both persons or operating apparatus when for any reason a person or object is caught in the doorway by the closing doors. In elevators, where both the car and shaftway doors must be operated and where some play between the car or cage and the shaftway is unavoidable in 20 successful operation, difficulty in the use of power operating means for the doors has been experienced owing to the necessity of operating door latches and the necessity of effecting a close engagement between the 25 door operating mechanism on the traveling car or cage and cooperating parts on the shaftway door.

An object of the invention is to provide 40 an improved power-actuated mechanism for the doors of elevators and the like which may be carried by the elevator car, with which the doors of both the cage and shaftway may be operated simultaneously; with 45 which the doors may be operated rapidly to within a short distance of their limits of travel and then be checked without impact or slamming; with which danger of injury to the operating mechanism or to a person 50 is avoided whenever the closing door strikes a person or obstruction; with which the starting stresses on the operating motor are reduced to a minimum; and with which the application of power to operate the door

in either direction will be interrupted automatically as the door reaches its limit of travel in either or both directions. A further object is to provide an improved door operating mechanism for elevators with which the cage or car may operate freely, 55 and with which the operation of the doors will be firm and without lost motion; with which the doors must be entirely closed and the shaftway door latched before the cage 60 can be operated and vice versa; and with which both cage and shaftway doors may be operated manually if necessary. A further object is to provide an improved door operating mechanism for accomplishing the 65 above objects which may be employed for operating doors of any width or for pairs of connected doors operating in opposite directions and which is exceptionally simple, durable, reliable, inexpensive, and positive, quiet, safe and rapid in operation. Other 70 objects and advantages will be apparent from the following description of an embodiment of the invention and the novel features will be particularly pointed out 75 hereinafter in claims.

In the accompanying drawings:

Fig. 1 is an elevation of a portion of an elevator shaftway and the cage opposite the door, and having door operating mechanism constructed in accordance with the invention, the doors of both the cage and shaftway being partially open;

Fig. 2 is a fragmentary elevation of a portion of the door operating mechanism, when both cage and shaftway doors are 90 closed and the cage is free to travel vertically in the shaftway;

Fig. 3 is an elevation of another part of the door operating mechanism showing the position of some of the operating parts 95 when the doors of both cage and shaftway are open to their full extent;

Fig. 4 is a plan of the mechanism shown in Figure 1;

Fig. 5 is a sectional elevation of the 100 mechanism, taken substantially along the line of 5—5 of Figure 2;

Fig. 6 is a sectional elevation of a portion of the device shown in Figure 5 with the parts in a different operated condition, 105 the section being taken approximately along the line 6—6 of Fig. 5.

Fig. 7 is a sectional plan of a portion of

the mechanism together with the latch of the shaftway door, the section being taken substantially along the line 7—7 of Figure 5;

Fig. 8 is an elevation of a portion of a shaftway door with the latch carried thereby;

Fig. 9 is an elevation of the mechanism for disconnecting the power operating mechanism from the doors;

10 Fig. 10 is a sectional elevation of the portion of the mechanism shown in Figure 9 and taken substantially along the line 10—10 of Figure 9; and

15 Fig. 11 is a perspective of the key employed in operating the mechanism shown in Figures 9 and 10.

In the illustrated embodiment of the invention, a sliding gate or door 1 (Figs. 1 and 4) is adapted to close a door opening 2 in a suitable shaftway 3 of an elevator. An extensible gate or door 4 is carried by the cage or car A of the elevator so as to close or open the doorway in the cage in a manner well known in the art. A suitable frame 5 is carried upon the car or cage, preferably upon the top wall thereof and adjacent the edge or side having the gate or door 4.

20 A shaft 6 (Fig. 5) extends through and is rotatably mounted in an enclosing casing 7 which is mounted upon the frame 5 in a suitable manner. A worm gear 8 is fixed upon the shaft for rotation therewith within the casing 7. A suitable motor 9 such as an electric motor, is mounted upon the frame 5 and at its lower end its drive shaft 10 (Fig. 2) enters the casing 7 (Fig. 5) and carries the worm screw 11 (Fig. 2) which meshes with and drives the worm wheel 8. A peripherally grooved pulley 12 is fixed upon 25 an end of the shaft 6 which extends outwardly through the casing 7, so that when the motor 9 operates it will, through the worm, worm wheel, and shaft 6, drive the pulley 12 in either direction dependent upon 30 the direction of rotation of the motor. The pulley 12 and the parts supporting and driving it are disposed adjacent the side edge of the doorway towards which the door of the cage is moved when it is closed.

35 At the opposite side of the car or cage, a bearing member 13 (Figs. 3 and 4) is pivotally mounted by a pin 14 in a suitable bracket 15 of the frame 5, so as to swing in a vertical plane and toward and from the pulley 12. A second grooved pulley 16 is 40 rotatably carried by the lower end of the bearing member 13 so as to be disposed in the plane of the pulley 12. A flexible driving cable 17 extends between and passes over both of the pulleys 12 and 16 so that the pulley 16 will be driven by the cable 17 from the pulley 12. A rod 18 extends rearwardly from the bearing member 13, passes loosely through an aperture in a lug or plate 45 19, and carries upon its projecting end an

adjustable nut 20 and a washer 21. A helical compression spring 22 is disposed on the rod 18 axially thereof between the plate 19 and the washer 21, so that when the nut 20 is adjusted along the threaded extremity 70 of the rod 18, the spring 22 will be compressed between the washer 21 and the plate 19. The spring 22 will therefore exert a pull upon the rod 18 in a direction to carry the bearing member 13 in a direction away 75 from the pulley 12 so as to hold the cable 17 taut.

80 A rail or track 23 is carried by the forward face of the frame 5 so as to extend parallel with the flexible cable 17 and also parallel with the travel of the doors or gates 1 and 4 which are to be operated. A carriage 24 is provided with anti-friction rollers 25 which embrace opposite sides of the track 23 and serve to mount the carriage 24 upon, and guide it along, the track or rail 23 for purposes which will herein-after appear. The ends of the cable 17 are connected together to form a continuous cable by a suitable coupling block 26 which 85 carries a pin 27 on one side face thereof. A link 28 is pivotally connected at one end to the pin 27 (Fig. 2) of the coupling block 26, and at its other end is pivotally coupled by a pin 29 to the carriage 24. When the cable 17 is given linear movement by the 90 operation of the motor 9, the link 28 connected between it and the carriage will cause the travel of the carriage along the track or rail 23 in a direction dependent upon the 95 direction of rotation of the motor 9.

95 A plate 30 (Figs. 2, 3, 5 and 6) extends downwardly from the forward end of the carriage and at its lower end is provided with an aperture 31 and near its junction 100 with the carriage with a strap 32 forming a loop. A casing 33, composed of two parts which are secured together in a suitable manner such as by screws 34, is slidably mounted between two vertically extending bars 35 of the cage door or gate 4, near the forward side edge thereof. The casing is provided with an extension tongue 36 which, when the casing is shifted upwardly, is adapted to enter the loop formed between the plate 30 and the strap 32, so as to couple the carriage 24 to the casing 33 and to the gate 4. A pawl or lever 37 is pivoted at 38 within the casing 33 and carries at its upper end an offset tongue or head 39 (Figs. 5, 6 105 and 9) which, when the casing is coupled by the tongue 36 to the carriage, is adapted to enter and pass through the aperture 31 in the lower end of the depending plate 30 of the carriage and also enter an aperture 40 110 in the casing which is then in alignment with the aperture 31. This lever or pawl 37 therefore serves to couple the casing to the carriage so as to prevent downward movement of the casing, which downward move- 115 120 125 130

ment would disconnect the casing and gate from the carriage. A spring 41 acting between a wall of the casing and the lever 37 serves to yieldingly hold the pawl or lever 37 in locking engagement with the depending plate 30 of the carriage.

Some of the vertically extending bars of which the gate 4 is composed are extended to form hangers 42, carrying rollers 43 which run upon a rail 44 that is supported in a position parallel with rail 23 by an angle member 45 forming a forward, upper, corner edge of the car A so as to permit of the travel of the car gate 4 in a direction parallel to the travel of the carriage 24. The other bars of the gate extend upwardly on opposite sides of the rail 23 to be guided thereby.

A vertically extending flange or rail 46 is provided upon the face of the casing 33 toward the shaftway door 1. The same face of the casing is also provided with struck up guides 47 which form, with the face of the casing, horizontally extending passages in which links 48 are mounted for reciprocation. These links pass through apertures in the flanges 46, and are connected to bell cranks 49 which are pivotally mounted at 50 upon the casing 33. The opposite ends of the links 48 are connected to a flange or rail 51 which extends parallel with the flange 46, so that when the links 48 are reciprocated in the struck up guides 47, the rail or flange 51 will be moved toward or from flange or rail 46 while remaining substantially parallel thereto. The corresponding ends of the rails are preferably made divergent. The arms of the bell cranks 49 which are not connected to the links 48 are connected together by a link 52 which extends upwardly into proximity to the carriage 24. A rod 53 is pivotally connected to the pivotal connection between the link 52 and one of the bell cranks 49, extends through an aperture in a lug 54 upon the casing 33, and upon its projecting end carries a nut 55 which is threaded thereon. A helical compression spring 56 surrounds the rod 53 between the nut 55 and the lug 54 so that when the nut 55 is adjusted along the rod, the spring will be compressed to different extents. The spring 56, by its reaction against the lug 54, will, if permitted to act, drive the rod 53 through the lug and rotate the bell crank levers 49 in a direction to shift the movable flange or rail 51 in a direction away from the relatively fixed rail or flange 46.

A bell crank lever 57 is pivotally mounted at 58 upon the carriage 24, and one arm of the bell crank is pivotally connected by a pin 59 to a link 60. The link 60 passes between the guide strip 61 and the carriage, and abuts against the upper end of the link 52. A rod 62 is pivotally connected at 63

to that arm of the bell crank which is connected to the link 60, passes loosely through an aperture in a lug 64 of the carriage, and upon its projecting end is provided with a nut 65 threaded thereon. A helical compression spring 66 surrounds the rod 62 between the nut 65 and the lug 64, and when the nut 65 is adjusted along the rod 62 the spring 66 will be compressed to variable extents. The spring 66, by its reaction upon the lug 64, tends to pull the rod 62 through the lug 64 and thus rotate the bell crank 57 in one direction. When the bell crank 57 is rotated by the spring 66, sufficiently to carry the arm thereof which is connected to the link 60 into a depending nearly substantially vertical position, the link 60 will be depressed and by its endwise abutting engagement with the link 52, will depress the latter against the action of the spring 56 and cause a shifting of the flange or rail 51 toward the relatively fixed rail or flange 46. It will be understood that to accomplish this, the spring 66 is made considerably stronger than the spring 56. A collar 62^a may be provided upon the rod 62 to engage with the lug 64 and limit rotation of the bell crank 57 by the spring 66 beyond a position in which the arm connected to link 60 is substantially vertical. The free end of the unconnected arm of the bell crank 57 is turned rearwardly, as at 67, into the path of the link 28 taken when its connection to the cable passes around the periphery of the pulley 12. When the carriage 24 is operated by the cable 17 forwardly, that is, in a direction to carry the gate 4 into a closed position, the coupling block 26 will reach and pass around with the pulley 12 and in doing so will carry the link 28 upwardly and cause it to engage and operate the rearwardly turned end 67 of the bell crank 57. This operation of the bell crank 57 against the action of the spring 66 carries the link 60 upwardly and releases the link 52. The link 52, thus released, is shifted upwardly by the spring 56 and moves the guide rail 51 away from the relatively fixed rail 46. This movement of the bell crank 57, sufficiently to entirely release the link 52, is preferably accomplished just after a theoretical line joining the pivotal connections of the link 28 to the cable and carriage passes through the axis of rotation of the pulley, and before the link reaches the position shown in Figure 2. A suitable resilient buffer 68 is mounted upon the frame 5 so as to be engaged by the coupling 26 when reaching the position shown in Fig. 2, in order that further movement of the link 28 may be prevented. The resistance of the spring 66 to the turning of the bell crank 57 by the link 28 serves also as a resilient bumper and assists somewhat in limiting movement of the link 28. The

action of the spring 66 alone as a buffer would be too uncertain and consequently the buffer 68 is provided to stop the coupling 26 exactly in the desired position.

- 5 A latch lever 69 is pivoted upon a pin 70 projecting from the inner face of the shaftway door or gate adjoining its forward side edge, and when the shaftway door or gate 1 is closed, the hooked end 71 of the latch lever 69 is adapted to engage behind the latch lug 72 of a latch casing 73, provided upon the shaftway frame. This latching engagement thus serves to hold the shaftway door in closed position. A roller 74 is pivotally mounted upon the pin 70 and a roller 75 is rotatably mounted by a pin 76 upon the outer end of an arm 77 which projects upwardly from the latch lever 69. The lever 69, with its angular extension arm 77, constitutes a bell crank lever. A compression spring 78 acts between a lug 79 on the door and a depending lug 80 of the latch lever 69 so as to normally rotate the latch lever in a direction to carry its hooked end 71 downwardly. A shoulder 81 on the latch lever 69 is adapted to abut against a fixed abutment 82 on the latch frame, and limit downward movement of the hooked end 71 under the action of the spring 78. When the latch lever 69 is in its downward position, (see Figs. 2 and 8) the roller 75 will be offset, in a horizontal direction, from the roller 74 for a purpose to be explained hereinafter. When the doors of the car and shaftway are closed, and the car is traveling in the shaftway, the guide rails 46 and 51 will pass on opposite sides of the rollers 74 and 75 and out of contact therewith (see Figs. 2 and 7). When the cage is stopped opposite the shaftway door and the motor 9 is operated to impart linear travel to the cable 17, the link 28 will be carried downwardly from the position shown in Figure 2, and as the coupling 26 passes downwardly around the pulley 12, the carriage 24 will be pulled forwardly through a small distance, which is sufficient to carry the relatively fixed rail 46 into contact with the periphery of the roller 74 of the latch of the shaftway gate. The concomitant downward movement of the link 28 from the position shown in Figure 2 will release the bell crank 57, whereupon the spring 66 will shift the bell crank 57 in a direction to force the link 60 downwardly and depress the link 52. The depression of the link 52 will shift the movable flange or rail 51 toward the relatively fixed flange or rail 46, and in moving, the rail 51 will engage with the periphery of the roller 75 and carry it into a position vertically above the roller 74, which movement causes a rocking of the latch lever 69 in a direction to carry the hooked end 71 out of engagement with the lug 72 and release the shaftway door for operation. As the car-

riage starts its main rearward or opening movement the rails 46 and 51, which now engage with the opposite sides of the roller 74, have a firm engagement with the door 1 of the shaftway and will carry it with the carriage in its opening or rearward movement. The car door or gate 4 will also move in an opening direction due to its positive connection with the carriage.

A bell crank 83 (Figs. 1 and 3) is pivoted at 84 to the frame 5, adjacent the position of the carriage when the doors have been opened to their maximum extent. A roller 85 is pivotally mounted upon one arm of the bell crank 83 so as to be engaged and operated by an inclined cam surface 86 of a cam 87 carried by the carriage 24, when the carriage reaches a position approximately at its limit of travel in a door opening direction. A spring 88 acts between an abutment 89 of the frame 5 and an arm of the bell crank 83, so as to normally hold the bell crank in a position with its anti-friction roller 85 within the path of travel of the cam 87.

A link 90 is pivotally connected at one end to that arm of the bell crank 83 which does not carry the roller 85, and at its opposite end is mounted for reciprocation in an aperture in a wall of a switch box 91. The end of the link 90 within the switch box also has a slideable bearing in a lug 92 projecting from the rear wall of the switch box. A bridging contact 93 is carried by the link 90 within the switch box 91. The contact 93 is insulated from the link 90 and, when the roller 85 is not engaged by the cam of the carriage, the contact bridges two circuit contact terminal posts 94 and 95, and by holding the link 90 will prevent movement of the bell crank 83 by the spring 88 beyond a position in which the roller 85 is within the path of the cam 87. The terminal posts 94 and 95 are connected by wires 96 and 97 to the electric motor 9 for controlling the operation of the motor 9 in one direction. Thus when the carriage 24 has reached approximately its limit of travel in a door opening direction, the operation of the bell crank 83, which is caused by its roller 85 riding up the cam surface 86, will cause a movement of the link 90 in a direction to carry the bridging contact bar 93 out of engagement with the terminal posts 94 and 95. This will arrest operation of the motor 9 in a door opening direction without preventing operation of the motor in the opposite direction. The link 28 by reason of its decreasing horizontal movement as the coupling 26 reaches and passes around the pulley 16 will check the opening movement of the doors and carriage, but a resilient buffer 16^a is also provided upon the frame 5 within the path of the coupling 26 to prevent overrunning thereof.

A bell crank 98 (Figs. 1 and 2) is pivotally mounted at 99 upon the frame 5, adjacent the limit of travel of the carriage in a door closing direction, and upon one arm 5 is provided with an anti-friction roller 100 which is within the path of a cam 101 that is carried by the carriage 24. The cam 101 is provided with an inclined cam surface 102, up which the roller 100 will ride when 10 the carriage reaches approximately its limit of travel in the door closing direction. The arm of the bell crank 98 which does not carry the roller 100 is pivotally connected to a link 103 which passes through and reciprocates in a wall of the switch box 91 and also in a lug 104 projecting from the rear wall of the switch box. An insulated bridging contact bar 105 is carried by the link 103 within the switch casing, and when 20 the roller 100 is within the path of the cam 101, the link will have a position such that the bar 105 will engage and bridge two terminal binding posts 106 and 107. The engagement of the bar 105 with the posts 106 and 107 limits the rotation of the bell crank 98 so as to hold the roller 100 normally within the path of the cam 101. The terminal posts 106 and 107 are connected by wires 108 and 109 respectively to the motor 9 for 30 controlling its rotation in a door closing direction. This control does not affect its rotation in the opposite direction. A spring 110 reacts between an abutment 111 of the frame 5 and an arm of the bell crank 98 so as to normally rotate the bell crank into 35 a position in which the roller 100 is within the path of the cam 101 and the bar 105 in contact with posts 106 and 107.

When the motor 9 is operated in a door 40 closing direction the carriage will travel toward the pulley 12 and carry both doors or gates in a closing direction. When the carriage has reached approximately its limit of travel in a closing direction, the roller 45 100 will ride up the inclined cam surface 102 of the cam 101, which has been brought beneath the roller by the travel of the carriage 24, and rock the bell crank 98 to operate the link 103. This operation of the 50 link 103 will carry the bridging contact bar 105 out of electrical contact with the terminal posts 106 and 107 and break that circuit of the motor 9 which is used when the motor operates in a door closing direction. 55 This interruption of the operation of the motor 9 is preferably timed to occur at approximately the completion of travel of the carriage.

During the final movement of the carriage, the coupling 26, to which it is connected, will pass around the periphery of the pulley 12 and because of this peripheral travel its horizontal component of travel will 60 decrease from a maximum rate at the point 65 where the coupling member 26 reaches the pulley 12 to "zero" where a theoretical line joining the pivotal connections of the link 28 to the coupling 26 and the carriage 24 passes through the axis of rotation of the pulley 12. The travel of the carriage and 70 doors in a door closing direction, which may be very rapid for the major portion of the movement will therefore by the crank action at the pulley 12 be quickly and effectively checked within a relatively short terminal 75 movement without impact or slamming of the doors, which terminal movement of the doors will comprise that which is produced while the coupling member 26 is traveling around a portion of the periphery of the 80 pulley 12.

A link or rod 112 is suspended from the frame 5 by links 113 and 114 which are articulately connected both to the frame and to the rod or link 112. A pin 115 extends laterally from the rod or link 112 and, when the latter is swung endwise in one direction, the pin 115 is adapted to engage and operate an arm 116, depending from the bell crank lever 98, so as to operate the bell crank in a 85 circuit opening direction. This operation is similar to that taking place when the carriage cam 101 acts upon the roller 100 to cause an opening of that circuit to the motor 9 which controls its door closing operation. 90 A safety member or link 117 is connected by parallel links 118 to the door or gate 4 of the car or cage, to form its extreme forward side edge, the links 118 being pivotally connected to both the gate and to the safety 95 member.

The upper end of the safety member 117 is provided with a lateral extension 119 carrying a depending pin 120, which pin is 100 adapted to normally rest upon the forward hanger 42 of the door or gate 4 and limit downward movement of the safety member 117 beyond a position in which the links 118 make an acute angle with the horizontal. 105 Thus, when a force is applied laterally to the safety member, it will be given a vertical movement by reason of the inclined position of the links 118. The lateral extension 119 of the safety member extends beneath the link 112 and is provided upon its upper face with pins 121 which embrace opposite sides of the link 112, so as to prevent displacement of the upper end of the safety member from beneath the link 112. Thus 110 when the safety member 117 is forced upwardly by forces applied laterally thereto, it will exert lateral forces on the link 112. When the link 112 rests upon the safety member, and when the latter is in its lowermost position, the links 113 and 114 will 115 also make acute angles to the horizontal so that vertical forces applied laterally to the link 112 will cause it to swing horizontally. Thus the vertical movement of the safety 120 member, such as would occur if the car door 125

130

should strike a person or obstruction during its closing movement, will cause a horizontal movement of the link 112, and the latter movement, by reason of the engagement of 5 the pin 115 with the depending arm 116 of the bell crank 98, will interrupt the connection between the circuit wires 108 and 109 in the switch box and thus prevent operation of the door in a closing direction by the 10 motor 9 as long as the obstruction remains in the doorway.

A contact pin 122 is carried by and insulated from the end of the latch lever 69, and when the latch lever is in latching engagement 15 with the stationary latch lug 72, the pin 122 is adapted to rest upon a terminal contact post 123 provided within the latch casing 73. A spring terminal member 124 is also secured within the latch casing 73 so 20 as to be engaged and flexed by the end of the pin 122 as the latch lever moves into latching engagement with the latch casing. The pin 122 thus bridges the terminal members 123 and 124 when the door 1 is latched. 25 Suitable wires 125 and 126 connect the terminal members 123 and 124, respectively, to the mechanism for controlling the travel of the cage or car in the shaftway, so that when 30 the circuit between the wires 125 and 126 is broken, which occurs when the latch lever is disengaged from the latch lug 72, the mechanism for operating the car or cage will be incapacitated. The details by which the wires 125 and 126 control the cage-operating 35 mechanism are not shown or described, because this feature per se is old in the art and is omitted here to avoid obscuring the novel features of the invention by old features.

It may happen that for some reason, such 40 as in case of mechanical or electrical trouble in the door operating mechanism, manual operation of the doors of both car and shaftway may be necessary or desirable. Accordingly, provision has been made for such 45 manual operation. A split casing 127 (Figs. 9 and 10) is secured to two of the vertical bars of the door or gate 4 of the cage, directly beneath the casing 33, by screws 128 which clamp the casing sections together, 50 and to the door bars, and by a screw 128^a which passes between the casing sections and also through one of the bars. A crank device 129 is rotatably mounted in the casing 127 and carries a crank pin 130 eccentrically of its axis of rotation. A connecting link 131 is disposed between the upright bars of the cage door and at its lower end enters the casing 127 through an aperture in 55 its upper wall. The end of the link 131 within the casing 127 is provided with a transversely extending, elongated slot 132, in which the crank pin 130 engages. Thus 60 as the crank 129 is rotated the connecting link 131 will be reciprocated vertically.

65 The upper end of the link 131 is offset as

at 133 so as to form a shoulder which abuts against the lower end wall of the casing 33 and then extends upwardly through an aperture 134 in the lower wall of the casing. The extreme upper end of the link 131 is 70 bent obliquely thereto as at 135 so as to serve as a cam which cooperates with a cam surface 136 on the pawl or lever 37. When the casing 33 is interlocked with the carriage 24 the crank device 129 is disposed in 75 such a position that a line joining the crank pin and the axis of rotation of the crank device 129 will make an acute angle with the vertical, as shown particularly in Figure 9.

The crank device 129 extends through one of the side walls of the casing 127 and is provided with a semi-cylindrical recess 137. A suitable operating key 138 is provided with a semi-cylindrical end 139 of a size corresponding to the recess 137 in the crank device, so that when the end 139 of the key is inserted into the semi-cylindrical recess 137 and rotated, the crank device 85 will be rotated. This rotation should be in a direction to carry the crank pin directly into a vertical position and impart a slight upward movement to the connecting link 131. This slight upward movement of the link 131 causes its shoulder at 133 to engage with the lower wall of the casing 33 and shift it upwardly through a short distance. This upward movement also lifts the latch 37 in the aperture 31 of the depending arm 30 of the carriage sufficiently to provide clearance for the latch end 39 of the latch lever 37.

A further rotation of the crank device 100 will carry the crank pin downwardly and cause a downward pull upon the connecting link 131. As the link 131 moves downwardly the cam end 135 thereof will engage with the cam surface 136 of the latch lever 37, and by reason of the fact that the casing 33 will remain in its upper position by its frictional engagement with the bars 35 of the cage or car gate, the action between the cam 135 and the cam surface 136 will pivot the latch or pawl 37 in a direction to 105 disengage the latch end 39 thereof from the aperture 31 of the depending arm 30 of the carriage 24. Further downward travel of the crank pin will cause engagement of a shoulder 140 of the link with the inner face of the bottom end wall of the casing 33 and through it pull the casing 33 downwardly upon the gate. This downward movement will disengage the extension 36 of the casing from beneath the strap 32 of the carriage, and the gate will then be free 110 for operation independently of the carriage 24. The casing 33 is provided in its sides with a slot 33^a to clear the depending extension 30 of the carriage when the casing is in 115 its lower disconnected position, and permit 120 125 130 135 140 145 150 155 160 165 170 175 180 185 190 195 200

travel of the casing past the carriage without interference therewith. This relative position of the casing and carriage is shown in Fig. 6.

5 A bar 141 is disposed between the vertical bars of the gate upon which the casing 33 is slidably mounted, so as to extend across the interior of the casing 33 in proximity to the pawl or lever 37. The lever 37 is provided with an intermediate oblique section 142 which, when the casing 33 is in its upper position, will lie just above the bar 141, with the upper end of the lever 37 overlying the bar 141. When the lever 37 is disengaged from the carriage and the casing 33 is pulled downwardly by operation of the crank device 129, the oblique portion of the lever 37 will pass to one side of the bar 141 and the upper offset end of the lever will 10 ride against the face of the cross bar 141. The cross bar 141 will thus hold the lever 37 in its retracted position until the casing 33 is returned to its upper position. Thus the car gate may be operated manually in 15 either direction without interference from the mechanical operating means.

The door 1 of the shaftway is provided with a cylindrical, transverse aperture 143 through which the semi-cylindrical end 139 of the key 138 may be passed and rotated therein. The door latch lever 69 is provided with an abutment surface 144 which, when the latch lever 69 is in its latched position in the latch casing 73, will extend 20 diametrically across the aperture 143 in the shaftway door. The semi-cylindrical end 139 of the key may thus be passed through the door aperture and into abutting relation with the abutment surface 144, so that 25 rotation of the key will cause a camming action between the semi-cylindrical end of the key and the abutment surface 144, which action will rock the latch lever in a direction to release it from the latch casing 73 and permit of manual operation of the door 30 in an opening direction.

When the gate is to be reattached to the carriage for power operation, the carriage is positioned with its depending extension 30 within the casing 33, and with the extension 36 of the casing directly beneath the strap 32 of the carriage. The crank device 129 is then given a reverse movement which operates the connecting link 131 upwardly. 35 As the link 131 moves upwardly its shoulder 133 will abut against the bottom wall of the casing 33 and shove the casing upwardly so as to project the extension 36 of the casing beneath the strap 32 of the carriage, and to carry the aperture 40 into alignment 40 with the aperture 31 of the depending extension 30 of the carriage. During this upward movement of the casing, the cam end 135 of the link 131 will have moved clear of

the cam surface 136 before the casing is engaged and operated by the shoulder 133, and unless otherwise restricted the lever 37 would be operated by its spring 41 in a direction to carry its latch end 39 beneath the extension 30 of the carriage. The lever 37, however, is held in retracted position by its engagement with the side of the cross bar 141 until the casing 33 has been shifted through substantially its entire upward movement, and as the oblique portion 142 75 of the lever 37 reaches the upper edge of the cross bar, the lever 37 will be projected by its spring 41 into the aperture 31 of the depending extension of the carriage.

While the casing 33 is in its lowermost 80 or disengaged position, a secondary extension 145 thereof, which normally runs in a space between the track 44 and the angle member 45 which supports it, will still remain in this space so as to prevent lateral 85 displacement of the casing, and will always hold the casing in a position to be projected upwardly into re-engagement with the carriage.

In the operation of the device, the doors 90 of both the car and shaftway will be normally closed, and the door 1 of the shaftway will be latched in closed position by the engagement of the latch lever 69 in the latch casing 73. In this position of the parts 95 which is shown in Figure 2, the fixed rail 46 will be spaced a short distance from the roller 74, and the relatively movable rail 51 will be at its maximum distance from the fixed rail 46, in which position it is also 100 spaced from both rollers 74 and 75. As the elevator car moves along the shaftway there will be sufficient clearance between the rails 46 and 51 and the rollers 74 and 75 105 to avoid danger of collision between them because of small lateral movements of the car which are necessary for free operation 110 of the car in the shaftway. The corresponding ends of the rails are also made slightly divergent so as to avoid possibility of collision of the rails with the rollers during the travel of the elevator car in the shaftway.

When the elevator car is stopped opposite 115 a door of the shaftway and the operator desires to open the door of the car and the door of the shaftway then adjacent thereto, he will close a suitable circuit, not shown, by switches located within the car, which will energize the electric motor 9 and cause it to operate in a door-opening direction. The motor 9 will act through the worm and worm wheel to drive the pulley 12 in a clockwise direction (Figure 2) and thereby impart linear travel to the flexible cable 17. 120 As the cable moves with the pulley 12, the link 28 will be pulled forwardly through a short distance, so as to impart a small for- 125

ward movement to the carriage that will carry the fixed rail 46 into engagement with the periphery of the roller 74.

At the same time the link 28 will descend 5 and release the bell crank lever 57, whereupon the spring 66 will rotate this bell crank lever in a direction to depress the link 60 connected thereto. This depression of the link 60 will cause a depression of the link 52, and the latter, by its connection through the bell crank 49 and links 48 to the relatively movable rail 51, will shift the movable rail toward the fixed rail until it engages with the periphery of the roller 74. 10 15 The rail 51 in moving toward the fixed rail 46 will engage with the roller 75, which is offset in a horizontal direction to one side of the roller 74, and by its engagement therewith will rock the latch lever 69 in a direction 20 to carry its latch nose 71 out of latching engagement with the latch lug 72. The unlatching movement of the lever 69 will carry its pin 122 out of bridging relation with the circuit controlling operation of the elevator 25 car in the shaftway, so that operation of the elevator car will be prevented as long as the latch is held in its unlatched position. This forward movement of the carriage, and the movement of the rail 51 toward the rail 46, 30 will occur before the rearward or door opening travel of the carriage 24 begins.

Continued movement of the coupling 26 around the periphery of the pulley 12 will cause it to propel the carriage 24 rearwardly, that is, in a door-opening direction, and by reason of the engagement of the rails on the carriage with the roller 74 on the shaftway door, and by reason of the connection between the carriage and the 40 car gate, both doors will be operated rearwardly, that is in an opening direction.

As soon as the carriage 24 has moved in an opening direction for a short distance, the roller 100 will be released from engagement with the cam 101 whereupon the spring 111 will operate the bell crank 98 and the link 103 to carry the bridging pin 105 into bridging relation with the circuit terminals 106 and 107, which bridging relation places the circuits of the motor 9 in a condition to permit of the operation of the motor 9 in a door-closing direction.

When the carriage 24 has reached approximately its rearward limit of travel, 55 the coupling 26 will reach the periphery of the pulley 16 and travel around the same in a manner similar to its travel around the driving pulley 12. During the travel of the coupling element 26 around the periphery of the pulley 16, its horizontal component of travel will decrease rapidly, and consequently will exert an increasing check upon the opening travel of the carriage and doors. The buffer 16^a will be en-

gaged by the coupling device 26 after its 65 travel for some distance around the periphery of the pulley 16, and will effectively limit the rearward travel of the carriage and doors.

When the carriage 24 has nearly completed its travel in a door-opening direction the cam 87 will engage the roller 85 and operate the bell crank 83 and the link 90 connected thereto, so as to carry the bridging pin 93 out of bridging relation with the 70 circuit terminals 94 and 95. The opening of the circuit between these terminals will prevent further operation of the motor 9 in a door-opening direction as long as the roller 85 is held in its upper position 75 by its engagement with the cam 87. It will be understood, of course, that the motor 9 may be stopped, started, or reversed by the operation of the switches within the control of the car operator at any time, even 80 during its travel in either direction.

When the operator desires to close the doors, he closes a suitable circuit to the motor 9 which causes its operation in an opposite direction, and through the driving 90 connection of the motor 9 to the pulley 12 the flexible cable 17 will be given a linear travel in an opposite direction. The crank-like action between the link 28 and the pulley 16 while the coupling element 26 is 95 in engagement with the periphery of the pulley, serves to place the carriage and doors in operation with a progressively increasing speed without placing an undue strain upon the motor 9. The carriage 24, 100 in moving forwardly, will carry the doors of both car and shaftway in a closing direction. As soon as the carriage carries the cam 87 out of contact with the roller 85 the spring 88 will operate the bell crank 105 83 and link 90 to carry the bridge pin 93 into bridging engagement with the circuit terminals 94 and 95, and again enable operation of the motor 9 in a door-opening direction whenever the switch controlled by 110 the operator for that purpose is operated.

If a person or object should be caught in any part of the doorway as the doors travel into closed position, the engagement of the safety member 117 with such person 115 or object will cause a movement of the safety member vertically upon the car gate, and this movement of the safety member will be upwardly. The safety member remains beneath the link 112 during its entire travel and will impart to said link a lateral force causing it to swing horizontally. The link 112 in moving horizontally will carry the pin 115 thereon against the depending arm 116 of the bell crank 98, and operate the latter in a direction 120 to shift the link 103 into the casing to a greater extent. By this movement, the

- bridge pin 105 will be carried out of bridging relation with the circuit terminals 106 and 107. The circuit between the wires 108 and 109, which is interrupted thereby, 5 controls the operation of the motor 9 in a door-closing direction, and consequently the motor 9 will be incapacitated and no further travel of the doors will result as long as the safety member remains in engagement 10 with the person or obstruction in the doorway.
- As soon as the obstruction or person is removed from the doorway, the safety member 117 will descend by gravity until the pin 15 120 thereon rests upon the hanger 42. The falling of the safety member releases the link 112 which swings in a reverse direction by the action of gravity, and also by the action of the spring 111 upon the bell crank 20 98. The bell crank 98 which is thus released, will be operated by the spring 111 to carry the link 103 in a direction to restore the bridge pin 105 into bridging relation with the circuit terminals 106 and 107, thus 25 automatically re-energizing the motor 9 and causing it to complete the door-closing movement.
- The spring 22 normally pulls the bearing element 13 in a direction away from the pulley 12, which serves to pull the pulley 16 in a direction to keep the cable 17 taut, and compensate for variations in the length of the cable 17 due to temperature changes. 30 If, for any reason, the doors stick, or their travel is obstructed, the spring 22 will yield and allow movement of the pulley 16 toward the pulley 12, and thereby slacken the cable 17 sufficiently to allow slippage thereof on the pulley 12. Thus the motor 9 might 35 continue to operate, but by reason of the slippage of the cable on the driving pulley, the doors and carriage will not be operated. This prevents burning out of, or other injury to the motor, such as might occur if the 40 travel of the doors and carriage were prevented without provision for stopping the motor or providing for slippage. When the carriage and doors have nearly reached their forward limit of movement, the coupling element 26 will reach the pulley 12 and pass around with its periphery, and then the horizontal component of travel of the coupling element 26 will decrease from a maximum rate of travel at the point where the 45 coupling element engages with the pulley 12, to zero at the point where the crank action of the link 28 causes a reverse movement of the carriage. This latter reverse movement will occur when a theoretical line 50 joining the pivot pins 27 and 29 of the link 28 passes through the axis of rotation of the pulley 12. This crank-like checking of the forward travel of the carriage and the doors, will quickly and effectively check the 55 doors in their closing movement without im- pact or slamming, and within a relatively short extent of their travel.
- When the carriage 24 has nearly completed its forward limit of movement in a door-closing direction the roller 100 will 70 ride up the cam surface 102 of the cam 101 which travels with the carriage, and by operating the bell crank 98 will open the circuit controlling the operation of the motor in a door-closing direction. The forward 75 travel of the carriage 24 will be far enough to carry the shaftway door into such a position that the latch lever 69 thereof may be in a position to move freely into latching engagement behind the latch lug 72, when 80 the latch lever is released. During the slight reverse movement of the carriage 24 following the door-closing forward travel, the fixed rail 46 carried by the carriage will re-cede slightly from the roller 74 and the link 28 85 will engage with and operate the bell crank lever 57 against the action of the spring 66. This operation of the bell crank 57 will result in an upward movement of the link 60 and a release of the link 52. Thereupon the 90 spring 56 will become active, shift the link 52 upwardly, and shift the rail 51 away from the fixed rail. The rail 51, in moving away from the fixed rail 46, will release the roller 75, and thereupon the spring 78 will 95 rotate the latch lever 69 into latching engagement with the lug 72 of the latch casting 73, which securely locks the shaftway door in closed position. The falling of the latch lever into latching position will carry 100 the pin 122 thereon into bridging relation with the circuit terminals 123 and 125, controlling the operation of the elevator car, and renders possible the operation of the car. The spring 66 will act somewhat as a 105 buffer, through the bell crank 57, in checking the travel of the link 28, but the resilient buffer 68 will always stop the coupling element 26 in a position to insure the proper 110 positioning of the carriage 24.
- When, for any reason, manual operation of the doors is desired, the key 138 may be inserted into the crank device 129 and operated to pull the casing 33 downwardly and disengage it from the carriage 24. The doors of both car and shaftway may then be operated manually to either open or closed positions. When the casing 33 is pulled downwardly to disconnect it from the carriage, the extension 145 thereon will 115 remain in the space between the track 44 and the angle member 45 supporting it so that the casing 33 will be kept in proper position to be reconnected to the carriage when the carriage is brought into proper position over the same. By a reverse operation, the doors may be re-connected to the carriage for operation therewith by the electric motor. If anyone on the outside of the shaftway desires to operate the shaftway 120 125 130

door, the key 138 may be inserted through the aperture 143 and rotated to cause a camming action between the semi-cylindrical end 139 of the key and the abutment surface 144 of the latch lever. This causes a rotation of the latch lever 69 to unlatched position, whereupon the shaftway door may be opened manually.

It will be noted that the entire mechanism, including the operating motor and gearing, for opening and closing concomitantly the doors of both car and shaftway is mounted upon and movable with the elevator car from floor to floor, so that a single operating mechanism will suffice for all of the doors of the shaftway as well as the door of the car.

While the invention has been described and illustrated in connection with elevators, it will be understood that the invention is applicable to the operation of doors in all cases where similar problems are encountered. It will also be understood that various changes in the details and arrangement of parts herein described and illustrated for the purpose of explaining the nature of the invention, may be made by those skilled in the art, within the principle and scope of the invention as expressed in the appended claims.

Claims:

1. A door operating device for elevators and the like comprising a pair of pulleys spaced apart in the direction of travel of the door to be operated, a cable running between and guided by the pulleys, means for causing linear movement of the cable, a link connected to the cable to be operated thereby, and a connection from the link to the door to be operated, whereby the door will be operated when the cable is given linear movement, the decreasing bodily speed of the link as its point of attachment to the cable reaches and moves around the said one of the pulleys serving to check without impact the travel of the door at its limit of travel in one direction.

2. A door operating device for elevators and the like comprising a pair of pulleys spaced apart in the direction of travel of the door to be operated, a cable running between and guided by the pulleys, means for causing linear movement of the cable, and means connecting to a point of the cable the door to be operated whereby the door will be operated by the linear travel of the cable, the travel of the door in one direction being checked without impact as the point of connection between the cable and door connecting means reaches and moves around one of the pulleys.

3. A door operating device for elevators and the like comprising a pair of pulleys spaced apart in the direction of travel of the door to be operated, a cable running between

and around the pulleys, means for driving one of the pulleys to cause linear travel of the cable, a connection between the cable and the door to be operated whereby the door will be operated by the linear travel of the cable, one of the pulleys being mounted for movement to slacken or tighten the cable, and yielding means constantly stressing the movable pulley in a direction to keep the cable taut but adapted to yield and allow the cable to slip when the travel of the door is prevented.

4. A door operating device for elevators and the like comprising a carriage, means supporting the carriage for travel in the direction of travel of the door to be operated, the carriage having a connection to the door, a pair of pulleys spaced apart in the direction of travel of the carriage, a cable passing between and in driving relation with the pulleys, means for causing linear travel of the cable, and a link articulately connected at opposite ends to the carriage and cable, whereby as the cable at its point of connection to the link reaches and passes around one of the pulleys the travel of the door in one direction will be checked without impact.

5. A door operating device for elevators and the like, comprising a carriage, means supporting the carriage for travel in the direction of travel of the door to be operated, the carriage having a connection to the door, a pair of pulleys spaced apart in the direction of travel of the carriage, a cable passing between and in driving relation with the pulleys, means for causing linear travel of the cable to operate the door, one of the pulleys being shiftable to slacken or tighten the cable, and resilient means constantly stressing the shiftable pulley in a direction to keep the cable taut, but adapted to yield and slacken the cable to permit it to slip when travel of the door is obstructed.

6. A door operating device for elevators and the like, comprising a cable, power actuated means including a pulley engaged by the cable for causing linear travel of the cable, a connection from the cable to the door to cause an operation of the latter when the cable is given linear movement, means for keeping the cable taut on the driving pulley and adapted, when travel of the door is obstructed, to yield and slacken the cable sufficiently to allow slippage on the driving drum.

7. A door operating device for elevators and the like comprising a pair of pulleys spaced apart in the direction of travel of the door to be operated, a cable running between and guided by the pulleys, means for causing linear movement of the cable, a track, a carriage running on said track and mechanically connected to the door to operate the same, and a connection between

the carriage and the cable whereby as the point of connection of the carriage to the cable travels in the stretch between the pulleys the carriage and door may be rapidly driven therefrom, and as the point of connection reaches and passes around with one of the pulleys, the carriage and door will be stopped without impact.

8. A door operating device for elevators and the like comprising a pair of pulleys spaced apart in the direction of travel of the door to be operated, a cable running between and guided by the pulleys, means for causing linear movement of the cable, a track, a carriage running on said track and mechanically connected to the door to operate the same, a connection between the carriage and the cable whereby as the point of connection of the carriage to the cable travels in the stretch between the pulleys the carriage and door may be rapidly driven therefrom and as the point of connection reaches and passes around with one of the pulleys, the carriage and door will be stopped without impact, and buffer means for preventing the travel of the cable substantially beyond the point at which the travel of the door is checked without impact.

9. A door operating device for elevators and the like comprising a pair of pulleys spaced apart in the direction of travel of the door to be operated, a cable running between and guided by the pulleys, power actuated means for causing linear movement of the cable, a track, a carriage running on the track and mechanically connected to the door to operate the same, a connection between the carriage and the cable whereby as the point of connection between the cable and carriage travels in the stretch between the pulleys, the carriage and door may be rapidly driven therefrom, and as the point of connection reaches and passes around with one of the pulleys, the carriage and door will be stopped without impact, and a limit device for rendering the power actuated means ineffective to drive the cable shortly before the travel of the door is completed.

10. A door operating device for elevators and the like comprising a pair of pulleys spaced apart in the direction of travel of the door to be operated, a cable running between and guided by the pulleys, power actuated means for causing linear movement of the cable, a track, a carriage running on the track and mechanically connected to the door to operate the same, a connection between the carriage and the cable whereby as the point of connection between the cable and carriage travels in the stretch between the pulleys, the carriage and door may be rapidly driven therefrom, and as the point of connection reaches and passes around

with one of the pulleys, the carriage and door will be stopped without impact, a limit device for rendering the power actuated means ineffective to drive the cable when the travel of the door is approximately completed, and buffer means for preventing travel of the cable, substantially beyond the point at which the travel of the door is checked without impact.

11. A door operating device for elevators and the like comprising a pulley, a cable passing over the pulley, power-actuated means for causing linear travel of the cable, a track, a carriage running on the track and mechanically connected to the door to operate the same, and a link pivotally coupled at one end to the cable and at its other end to the carriage, whereby as the point of coupling of the link to the cable travels towards the pulley the door will be driven at the same rate, and as the point of coupling reaches and passes around with the pulley the link will act as a crank and stop the carriage and door without impact.

12. A door operating device for elevators and the like comprising a pulley, a cable passing over the pulley, power-actuated means for causing linear travel of the cable, a track, a carriage running on the track and mechanically connected to the door to operate the same, a link pivotally coupled at one end to the cable and at its other end to the carriage, whereby as the point of coupling of the link to the cable travels towards the pulley the door will be driven at the same rate, and as the point of coupling reaches and passes around with the pulley the link will act as a crank and stop the carriage and door without impact, a cam traveling with the carriage, and a limit device in position to be operated by the cam at approximately the end of the travel of the door and carriage and render the power actuated means ineffective to drive the cable.

13. A door operating device for elevators and the like comprising a pulley, a cable passing over the pulley, power-actuated means for causing linear travel of the cable, a track, a carriage running on the track and mechanically connected to the door to operate the same, a link pivotally coupled at one end to the cable and at its other end to the carriage, whereby as the point of coupling of the link to the cable travels towards the pulley the door will be driven at the same rate, and as the point of coupling reaches and passes around with the pulley the link will act as a crank and stop the carriage and door without impact, a cam traveling with the carriage, a limit device in position to be operated by the cam at approximately the end of the travel of the door and carriage and render the power actuated means ineffective to drive the cable,

and buffer means adapted to limit travel of the point of coupling to a small increment of movement after the door has been checked.

14. A door operating device for elevators and the like comprising a pulley, a cable passing over the pulley, power-actuated means for causing linear travel of the cable, a track, a carriage running on the track and mechanically connected to the door to operate the same, a link pivotally coupled at one end to the cable and at its other end to the carriage, whereby as the point of coupling of the link to the cable travels towards the pulley the door will be driven at the same rate, and as the point of coupling reaches and passes around with the pulley the link will act as a crank and stop the carriage and door without impact, and a device carried by the door edge and operable upon the limit device to render the power-actuated means ineffective whenever the door edge presses against an object obstructing closing of the door.

15. A door operating device for elevators and the like comprising a pair of pulleys spaced apart in the direction of travel of the door to be operated, a cable running between and guided by the pulleys, power-actuated means for causing linear movement of the cable, means connecting to a point of the cable the door to be operated whereby the door will be operated by the linear travel of the cable, the travel of the door in one direction being checked without impact as the point of connection between the cable and door connecting means reaches and moves around one of the pulleys, a limit device for rendering the power actuated means automatically ineffective when the movement of the door is approximately complete, and means movably carried by the door to project beyond the side edge thereof and operable upon the limit device, when moved relatively to the door in engaging an obstruction during the travel of the door, to render the power actuated means ineffective, whereby the travel of the door will be halted until the obstruction is removed.

16. A door operating device for elevators and the like comprising a power actuated device for operating the door in a closing direction, means for preventing closing of the door by the power actuated device, including a controlling member substantially co-extensive with the travel of the door, and a safety device carried by the door along its side edge, and operable on the door when it strikes an obstruction in the closing travel of the door, for engaging and operating the controlling member to check the closing operation of the door as long as the door engages with the obstruction.

17. A door operating device for elevators and the like comprising a power-actuated

device for operating the door in a closing direction, a member substantially co-extensive with the travel of the door and disposed adjacent to the door, means for mounting the member so as to have a vertical component of movement when a force is applied laterally thereto, a safety device carried by the door along its forward side edge and operable on the door, when it strikes an obstruction in the closing travel of the door, for engaging and operating the member vertically, and means operable by the member in moving vertically for interrupting the application of a closing force to the door by the power actuated device as long as the door remains in engagement with the obstruction.

18. A door operating device for elevators and the like comprising a power actuated device for operating the door in a closing direction, a controlling member disposed parallel and adjacent to the door and substantially co-extensive with its travel, links suspending the controlling member for swinging movement in the direction of travel of the door, means controlled by the swinging movement of the member in one direction for causing a discontinuance of a closing force to the door by the power actuated device, a safety device carried by the door with at least a portion extending along the forward side edge of the door and operable relatively to the door, when it strikes an obstruction in the closing travel of the door, for engaging and swinging the controlling member in said one direction to check the closing of the door by the power actuated device as long as the door remains in engagement with the obstruction.

19. A door operating device for elevators and the like comprising a power actuated device for operating the door in a closing direction, a controlling member disposed parallel and adjacent to the door and substantially co-extensive with its travel, links suspending the controlling member for swinging movement in the direction of travel of the door, a limit device normally operative to stop the operation of the door by the power actuated device when the door completes its closing movement, said limit device having an operating arm extending into proximity to the controlling member, means on the controlling member for engaging and operating the arm of the limit device to check the power operation of the door when the member is swung in one direction, a safety device carried by the door with at least a portion extending along the forward side edge of the door and operable relatively to the door, when it strikes an obstruction in the closing travel of the door, for engaging and swinging the controlling member in said one direction to check the

closing of the door by the power actuated device as long as the door remains in engagement with the obstruction.

20. A door operating device for elevators and the like, comprising a power actuated device for operating the door in a closing direction, a safety member extending along and forming the forward side edge of the door, means for mounting the safety member on the door so as to be movable vertically thereon when a force is applied laterally thereto, and means adapted to be operated by said safety member in all positions of the door for rendering the power actuated device ineffective to close the door whenever the safety member strikes an obstruction and is operated vertically on the door thereby.

21. A door operating device for elevators and the like comprising a carriage connected to the door for operating it, power actuated means for operating the carriage in a closing direction, means operable by the carriage when it reaches approximately its closed position for stopping the application of a closing force to said door by said power actuated device, and means, including a safety member carried by the door, operable upon the said stopping means, when the safety member strikes an obstruction in the doorway, for holding in abeyance the door closing effort of the power actuated means as long as the safety member remains in engagement with the obstruction.

35. 22. A door operated device for elevators and the like comprising a carriage connected to the door to operate the same in both directions, electrically operated means connected to the carriage to operate the same in both directions, switching means controlling the direction of operation of the carriage and door by the electrically driven means, means actuated by the carriage at approximately the open and closed positions of the door for operating the switching means to limit operation of the carriage and door by the electrically driven means beyond those positions, and a safety device including a part carried by the door and movable relatively thereto when it engages an obstruction during the closing movement of the door for also operating the switching means to prevent further closing of the door by the electrically operated means as long as the obstruction remains.

23. In a door operating device for elevators and the like, a carriage carried by the car for travel thereon in the direction of travel of the door, a latch lever carried by the door to be operated, a stationary latch member with which the latch lever engages when the door is closed, a pair of rails carried by the carriage which, when the door is closed and the car is traveling will pass free of the latch, one of the rails being fixed

on the carriage and the other movable toward and from the fixed rail, and mechanical means connected to the carriage to impart thereto a small movement in a closing direction to carry the fixed rail into contact with the latch and simultaneously shift the movable rail into engagement with the latch lever on the other side of its pivot, the shifting of the movable rail acting upon the latch lever to release it from the stationary latch member, continued operation of the mechanical means in the same direction carrying the carriage and door in an opening direction.

24. In a door operating device for elevators and the like, having a car moving along a shaftway, a latch lever on the door to be operated and having an operating end disposed horizontally at one side of its pivot when the lever is in latched position, spaced rails carried by the car, normally clearing the latch during the travel of the car in the shaftway and relatively movable to decrease the clearance space between them, and a mechanical device carried by the car and adapted when operated in one direction to shift the rails into contact with said latch lever on opposite sides of its pivot, operate the said end of the latch lever vertically above its pivot into unlatched position, and then shift the door in an opening direction.

25. In a door operating device for elevators and the like, a latch device normally holding in closed position the door to be operated, and means carried by the car and movable thereon first to move the door slightly further in a closing direction to permit free operation of said latch device and concomitantly engage and operate the latch device to release the door, and then subsequently to operate the door in an opening direction.

26. A door operating device for elevators and the like, comprising a cable, power actuated means including a pulley engaged by the cable for causing linear travel of the cable, a carriage connected to the cable to be operated thereby when the cable is given linear movement, the point of connection between the carriage and the cable reaching and passing partly around the pulley in operating the carriage in one direction, a latch on the door to be operated, and means carried by the carriage and adapted when the cable is operated in an opposite direction to move into engagement with the latch, operate the latch to release the door, and then by continued movement of the cable in the same direction operate the door in an opening direction.

27. In a door operating device for elevators and the like, a pivoted bell crank latch lever on the door to be operated, an operating projection carried by the door in sub-

stantial vertical alignment with the pivot of the latch lever, spaced rails having relative movement toward and from one another and traveling vertically with the car, and means adapted to move the rails into contact with opposite sides of the operating projection, concomitantly engage and operate the bell crank lever to release the door, and then operate the door in an opening direction by the engagement of the rails with the operating projection.

28. A door operating device for elevators and the like, comprising spaced pulleys, a cable passing over and guided by said pulleys for linear travel in the direction of travel of the door to be operated, power actuated means for causing linear movement of the cable in either direction, a carriage carried by the elevator car and mounted for travel in a direction parallel with the travel of the door, a link articulately connected at its ends to the cable and to the carriage whereby the carriage will be operated by the cable, and as the connection of the link to the cable reaches and travels with the periphery of one of the pulleys the travel of the carriage will be brought to a stop without impact as the link passes through the axis of rotation of said one pulley and then operated in a reverse direction a short distance to its normal position when the car is operating in the shaftway, a fixed rail on the carriage, a second rail carried on the carriage for movement laterally toward and from the fixed rail, a projection on the door to be operated, the rails normally passing freely on opposite sides of the projection during their travel with the car along the shaftway, means rendered effective by the link while passing toward the axis of rotation of said one pulley in starting the carriage in operation from its said normal position for shifting the movable rail into engagement with the projection, the slight forward movement of the carriage, occurring concomitantly, carrying the fixed rail into engagement with the other side of the projection, a latch normally preventing operation of the door, and operated to release the door by engagement therewith by one of the rails while approaching the door projection, continued movement of the carriage by the cable operating the door in an opening direction through the engagement of the rails with the projection on the door.

30. A door operating device for elevators and the like, comprising a pulley, a cable passing around the pulley and extending tangentially therefrom, means for causing linear travel of the cable, a carriage, a link articulately connected at its ends to the cable and to the carriage, whereby the carriage will be operated when the cable is given linear movement, the link and pulley acting as a crank device when the connection between the link and cable reaches and passes around with the pulley, to stop the carriage without impact and reverse its travel, means for limiting to a slight extent the reverse movement of the carriage by the travel of the cable beyond that necessary to stop the carriage, all of the above parts being carried by the elevator car, and an abutment on the door to be operated against which the carriage engages to operate the door in a closing direction, the slight reverse movement of the carriage serving to provide clearance between the abutment of the door and the part of the carriage operating against the abutment as the carriage travels with the elevator car in the shaftway.

29. A door operating device for elevators and the like, comprising spaced pulleys, a cable passing over and guided by said pulleys for linear travel in the direction of travel of the door to be operated, power actuated means for causing linear movement of the cable in either direction, a carriage carried by the elevator car and mounted for travel in a direction parallel with the travel of the door, a link articulately connected at its ends to the cable and to the carriage whereby the carriage will be operated by the cable, and as the connection of the link to the cable reaches and travels with the

periphery of one of the pulleys the travel of the carriage will be brought to a stop without impact as the link passes through the axis of rotation of said one pulley and then operated in a reverse direction a short distance to its normal position when the car is operating in the shaftway, a fixed rail on the carriage, a second rail carried on the carriage for movement laterally toward and from the fixed rail, a projection on the door to be operated, the rails normally passing freely on opposite sides of the projection during their travel with the car along the shaftway, means rendered effective by the link while passing toward the axis of rotation of said one pulley in starting the carriage in operation from its said normal position for shifting the movable rail into engagement with the projection, the slight forward movement of the carriage, occurring concomitantly, carrying the fixed rail into engagement with the other side of the projection, a latch normally preventing operation of the door, and operated to release the door by engagement therewith by one of the rails while approaching the door projection, continued movement of the carriage by the cable operating the door in an opening direction through the engagement of the rails with the projection on the door.

31. A door operating device for elevators and the like, comprising a pulley, a cable passing around the pulley and extending tangentially therefrom, means for causing linear travel of the cable, a carriage, a link articulately connected at its ends to the cable and to the carriage whereby the carriage will be operated when the cable is given linear movement, the link and pulley

30. A door operating device for elevators and the like, comprising a pulley, a cable passing around the pulley and extending tangentially therefrom, means for causing linear travel of the cable, a carriage, a link articulately connected at its ends to the cable and to the carriage whereby the carriage will be operated when the cable is given linear movement, the link and pulley

- acting as a crank device, when the connection between the link and cable reaches and passes around with the pulley, to stop the carriage without impact and reverse its travel, means for limiting to a slight extent the reverse movement of the carriage by the travel of the cable beyond that necessary to stop the carriage, all of the above parts being carried by the elevator car, an abutment on the door to be operated against which the carriage engages to operate the door in a closing direction, the slight reverse movement of the carriage serving to provide clearance between the abutment of the door and the part of the carriage operating against the abutment, as the carriage travels with the elevator car in the shaftway, door engaging means mounted on the carriage for movement into and out of engagement with a forwardly facing abutment surface on the door and yieldingly pressed toward a position in which it clears the door as the car travels in the shaftway, means adapted when released to operate the preceding means in a direction to engage the door, said last named means being operated by the link in moving into its limited position after the door is closed by the carriage, to permit operation of the door engaging means into a condition to clear the door as the car travels in the shaftway.
32. A door operating device for elevators and the like comprising a carriage operable on the elevator car in a direction parallel with the travel of the door to be operated, a device for operating the carriage in both directions, the carriage at its forward limit of travel being given a slight reverse movement, and means on the carriage adapted to engage with and push the door closed as the carriage is moved forwardly, the slight reverse movement providing clearance between the carriage and the door when the carriage moves with the car in the shaftway.
33. A door operating device for elevators and the like comprising a carriage operable on the elevator car in a direction parallel with the travel of the door to be operated, a device for operating the carriage in both directions, the carriage at its forward limit of travel being given a slight reverse movement, means on the carriage adapted to engage with and push the door closed as the carriage is moved forwardly, the slight reverse movement providing clearance between the carriage and the door when the carriage moves with the car in the shaftway, means also on the carriage in a position normally to clear the door as the car and carriage move in the shaftway and movable into engagement with the door to form the connection between the door and carriage during the complete rearward movement of the carriage, and means operative automatically during the slight forward move-
- ment of the carriage preceding its door opening movement for causing operation of the preceding means to engage with the door and serve to operate it in an opening direction as the carriage operates rearwardly.
34. A door operating device for elevators and the like comprising a carriage operable on the elevator car in a direction parallel with the travel of the door to be operated, a device for operating the carriage in both directions, the carriage at its forward limit of travel being given a slight reverse movement, means on the carriage adapted to engage with and push the door closed as the carriage is moved forwardly, the slight reverse movement providing clearance between the carriage and the door when the carriage moves with the car in the shaftway, means also on the carriage in a position normally to clear the door as the car and carriage move in the shaftway and movable into engagement with the door to form the connection between the door and carriage during the complete rearward movement of the carriage, means operative automatically during the slight forward movement of the carriage preceding its door opening movement for causing operation of the preceding means to engage with the door and serve to operate it in an opening direction as the carriage operates rearwardly, a latch device normally holding the door closed and operable to release the door by the said

movable means on the carriage when the said movable means is moved to engage the door, and circuit means controlled by the latch for preventing operation of the car 5 when the door is unlatched.

36. A door operating device for elevators and the like comprising a carriage operable on the elevator car in a direction parallel with the travel of the door to be operated, a 10 device for operating the carriage in both directions, the carriage at its forward limit of travel being given a slight reverse movement, and a rail on the carriage extending in the direction of travel of the elevator car 15 adapted to engage with and push the door closed as the carriage is moved forwardly, the slight reverse movement of the carriage providing clearance between the rail and the door when the carriage and rail move with 20 the car in the shaftway.

37. A door operating device for elevators and the like comprising a carriage operable on the elevator car in a direction parallel with the travel of the door to be operated, a 25 device for operating the carriage in both directions, the carriage at its forward limit of travel being given a slight reverse movement, a rail on the carriage extending in the direction of travel of the elevator car adapt- 30 ed to engage with and push the door closed as the carriage is moved forwardly, the slight reverse movement of the carriage pro- 35 viding clearance between the rail and the door when the carriage and rail move with 40 the car in the shaftway, a second rail on the carriage extending parallel with and movable toward and from the first rail, said second rail normally clearing the door as 45 the car and carriage move together in the 50 shaftway and adapted to engage with the door when moved toward the first rail, and means operative automatically during the 55 slight forward movement of the carriage preceding the door opening movement for causing 60 operation of the second rail into engagement with the door, whereby upon the following rearward movement of the carriage the second rail will operate the door rearwardly to open position.

38. A door operating device for elevators and the like comprising a carriage operable on the elevator car in a direction parallel with the travel of the door to be operated, a device for operating the carriage in both 55 directions, the carriage at its forward limit of travel being given a slight reverse movement, a rail on the carriage extending in the direction of travel of the elevator car adapted to engage with and push the door 60 closed as the carriage is moved forwardly, the slight reverse movement of the carriage providing clearance between the rail and the door when the carriage and rail move with the car in the shaftway, a second rail on 65 the carriage extending parallel with and

movable toward and from the first rail, said second rail normally clearing the door as the car and carriage move together in the shaftway and adapted to engage with the door when moved toward the first rail, means 70 operative automatically during the slight forward movement of the carriage preceding the door opening movement for causing operation of the second rail into engagement with the door, whereby upon the following 75 rearward movement of the carriage the second rail will operate the door rearwardly to open position, and a latch device normally holding the door closed and operable to release the door through engagement therewith by one of the rails as the latter moves into engagement with the door.

39. In a door operating device for elevators and the like, a projection on one face of the door to be operated, a latch lever pivoted to the door, a latch part on the shaftway frame with which the latch lever co-operates to hold the door closed, a carriage movable with the elevator car and having a fixed rail thereon within the path of the projection when the door opens and extending in the direction of travel of the car, a second and substantially parallel rail carried by the carriage on the opposite side of the projection for movement toward and from the fixed rail, means for operating the carriage rearwardly and forwardly with respect to the travel of the door, the forward movement of the carriage by the operating means terminating in a short reverse movement after pushing the door closed by the engagement of the projection by the fixed rail so as to provide travel clearance between the rail and projection, the rearward movement of the carriage starting with a short forward movement to carry the fixed rail into contact with the projection, and means operative automatically and concomitantly with said short starting movement for carrying the movable rail into contact with the door projection and concomitantly operating the latch lever to release the door, the succeeding main movement of the carriage carrying the door to an open position, said last specified means being also operative during the short reverse movement in the closing operation of the door by the carriage to carry the movable rail away from the projection to provide travel clearance and release the latch lever.

40. In a door operating device for elevators and the like, a projection on one face of the door to be operated, a latch lever pivoted to the door, said lever having a roller carried eccentrically thereon with respect to the pivot and also slightly offset horizontally with respect to the projection, a latch part on the shaftway frame with which the latch lever co-operates to hold the door closed, a carriage movable with the elevator car and

- having a fixed rail thereon within the path of the projection when the door opens and extending in the direction of travel of the car, a second and substantially parallel rail 5 carried by the carriage on the opposite side of the projection for movement toward and from the fixed rail, means for operating the carriage rearwardly and forwardly with respect to the travel of the door, the forward 10 movement of the carriage by the operating means terminating in a short reverse movement after pushing the door closed by the engagement of the projection by the fixed rail so as to provide travel clearance between the rail and projection, the rearward movement of the carriage starting with a short forward movement to carry the fixed rail into contact with the projection, and means operative automatically and 15 comitantly with said short starting movement for carrying the movable rail into contact with the door projection, the relative approach of the rails causing one of them to engage the offset roller and operate the latch lever to release the door, the succeeding main movement of the carriage carrying the door to an open position, said last specified means being also operative during the short reverse movement in closing operation 20 of the door by the carriage to carry the movable rail away from the projection to provide travel clearance and release the latch lever.
41. In a door operated device for elevators and the like, means adapted to operate the door including a traveling carriage, an electric motor connected to drive said operating means, means including a switch for controlling operation of the motor in one direction, a cam carried by the carriage, operating means for said switch having a part projecting into the path of the cam to be reached and operated thereby to open the circuit of the motor when the carriage has 25 operated the door approximately to its limit of travel in one direction, and safety mechanism including a part moving with the door adapted to also operate the switch and stop the motor operation when the said part moving with the door strikes an obstruction in the doorway.
42. In a door operated device for elevators and the like, means adapted to operate the door including a traveling carriage, an electric motor connected to drive said operating means in opposite directions dependent upon the desired direction of operation of the door, control elements arranged for operation by the carriage at approximately its limits of travel in each direction, a switch device controlled by each control element and adapted when operated to stop operation of the motor in a direction to move the carriage farther in the direction of the control element, and a safety device also 30 operative on the switch device to stop the operation of the motor in a door closing direction when the door strikes an obstruction in the doorway.
43. In a door operated device for elevators and the like, means adapted to operate the door including a traveling carriage, an electric motor connected to drive said operating means in opposite directions dependent upon the desired direction of operation of the door, control elements arranged for operation by the carriage at approximately its limits of travel in each direction, a switch device controlled by each control element and adapted when operated to stop operation of the motor in a direction to move the carriage farther in the direction of the control element, means normally stressing said elements into the path of the carriage to close the circuits, and a safety device also 35 operative on the control element which limits operation of the motor in the door closing direction for interrupting the operation of the motor in a door closing direction when the closing door strikes an obstruction in the doorway, and adapted to start operation of the motor automatically when the obstruction is removed.
44. In a door operating device for elevators and the like, a carriage traveling in a direction parallel to the travel of the door to be operated, a casing slidable on the door into and out of coupled engagement with the carriage, a latch in said casing for holding it in coupled relation to the carriage, and a crank device connected to the casing to operate the latch to unlatch the casing from the carriage and then slide the casing out of coupled relation with the carriage.
45. In a door operating device for elevators and the like, a carriage traveling in a direction parallel to the travel of the door to be operated, a casing slidable on the door into and out of coupled engagement with the carriage, a latch in said casing for holding it in coupled relation to the carriage, a spring normally pressing the latch into engaging relation with the carriage, and a bar on the gate and disposed within the casing and also within the path of the latch when the latter moves with the casing out of coupled relation with the carriage, whereby the latch will be held in disengaged position until the casing is returned to the position on the gate which it occupies when coupled to the carriage.
46. In a door operating device for elevators and the like, a carriage traveling in a direction parallel to the travel of the door to be operated, a casing slidable on the door into and out of coupled engagement with the carriage, a latch in said casing for holding it in coupled relation to the carriage, a spring normally pressing the latch into engaging relation with the carriage, a bar on

the gate and disposed within the casing and also within the path of the latch when the latter moves with the casing out of coupled relation with the carriage, whereby the latch will be held in disengaged position until the casing is returned to the position on the gate which it occupies when coupled to the carriage, a link entering and sliding in the casing with a lost motion connection thereto
10 by which the casing can be shifted into and out of coupled relation with the carriage, and a crank device connected to the link to reciprocate the same, the link having on the end within the casing a cam portion dis-
15 posed to engage with and operate the latch into a disengaged position when the link is pulled downwardly and operative upon the latch before the lost motion between the link and casing is taken up by the down-
20 ward movement of the link.

47. In a door operating device for elevators and the like, a carriage traveling in a direction parallel to the travel of the door to be operated, a casing slideable on the door into and out of coupled engagement with the carriage, a latch in said casing for holding it in coupled relation to the carriage, a link entering and sliding in the casing with a lost motion connection thereto by
25 30 which the casing can be shifted into and out

of coupled relation with the carriage, and means for reciprocating the link in opposite directions and through it shift the casing, the link on the end within the casing having a cam portion disposed to engage with and operate the latch into a disengaged position when the link is pulled downwardly and operative upon the latch before the lost motion between the link and casing is taken up by the downward movement of the link. 40

48. A door operating device for elevators and the like, comprising a cable, power actuated means including a pulley engaged by the cable for causing linear travel of the cable, a connection from the cable to the door to cause an operation of the latter when the cable is given linear movement, means for keeping the cable taut on the driving pulley and adapted, when travel of the door is obstructed, to yield and slacken the cable sufficiently to allow slippage on the driving drum, and means for stopping the action of the power actuated means automatically when the door reaches its limits of travel in each direction. 45 50 55
